UNITED STATES PATENT OFFICE.

JOHN M. STEWART, OF CLARENDON, VIRGINIA.

ELECTRICAL CONDENSER.

Application filed November 4, 1924. Serial No. 747,877.

My invention relates generally to electrical condensers and more particularly to variable air condensers used in radio circuits.

An object of the invention is to provide a condenser having dual control through a single knob.

Another object of the invention is to provide a condenser particularly adaptable for aircraft sets.

10 A further object is to provide a condenser permitting the greatest economy in panel board space without complicating the movable plate control.

15 A still further object is to provide a condenser which reduces the cost of manufacture to a minimum without sacrificing any of the advantages of dual control.

20 With these and other objects in view, the invention consists in the construction, combination, and arrangement of parts as will be hereinafter described.

Reference is to be had to the accompanying drawings forming part of this specification, in which like reference characters indicate corresponding parts throughout the several views, and in which

Figure 1 is a sectional view showing my dual control means.

Figure 2 is a perspective view partly broken away.

Figure 3 is a fragmentary perspective view of the plate used therein, and

Figure 4 is a sectional view of a modification particularly adapted for aircraft sets.

35 Referring more particularly to the drawings, 5 indicates a panel board to which the condenser top 6 is attached by spacers 7. The usual stationary plate assembly 8 and movable plate assembly 9 are contained within the condenser. The movable plates are secured to the spindle 10 which is provided with an enlarged recessed head 11 and a guideway 12 extending therefrom. A plate 15 having integral upstanding arms 16 and laterally extending ears 17, the purpose of which will be later explained, is secured to a compound gear 23 in any suitable manner. This plate, which may be stamped from a single piece of material, is also provided with a 180 degree slot 19 permitting movement thereof about a stud 20 passing through an opening 21 in the top 6 and clamped thereto by any suitable means, such as a screw 22. The brass compound gear 23, 55 that is, a gear having an extended toothed periphery 24 and an interiorly beveled hub

portion 25, is secured to the head 11 by sweating, or by a key 18, as shown. It is to be understood that the bevel may be constructed for either friction, milled or toothed drive. The stud 20 carries an insulated gear 26 having an elongated hub which supports a metal, preferably brass, gear 27 having a beveled contacting surface constructed similarly to that of hub 25. The gear 26 engages with the toothed portion of gear 23. A shaft 28 passing through the condenser dial 29 and separated therefrom by the bearing 30 has removably secured thereon at its interior end a double beveled gear 31 the surfaces of which are constructed similarly to the surfaces of 25 and 27 with which it respectively engages. The gear may be made in one piece as in Figure 1 or two pieces as in Fig. 4.

75 The interior end of the shaft is reduced forming a guidepin 14 which slides in the guideway 12 keeping it true assuring positive engagement of the gears. A spring 13 within the recessed head and which bears against a washer 38 placed between it and the large end of the shaft to prevent its twisting upon rotation of the shaft, keeps the shaft in its outward position so that gears 31 and 27 are in mesh. A knob 32 actuates the shaft 28, which normally is held 80 in the position shown in Figure 1, so as to cause the gear 31 to engage with the gear 25, and to cause rotation of the spindle 10 direct or through the gearing, depending upon with which gear the gear 31 is engaged. 85 In its normal position, or that shown in Figure 1, the condenser is ready for fine adjustment, main adjustment being obtained by pressing in the knob disengaging gear 31 from 27 and engaging it with gear 25. In 90 operation fine adjustment is a more lengthy manipulation than main adjustment which is the reason for having the condenser in position for such adjustment. To prevent the end of the slot 19 coming into abrupt 100 contact with the stud 20, which might cause injury to the delicate construction of a condenser, I provide a buffer or brake 33 on the top 6 in such position that the ears 17 will contact therewith as the plate 15 approaches 105 the limits of its travel in either direction. The dial 29 is provided with the usual degree markings, as may be seen in Figure 2 and an indicating mark on the panel 5 co-acts there- 110 with in adjustment of the movable plate assembly, and, in order to reduce to a minimum the capacity effect of the body, the

dial is electrically grounded to the panel through connection 34.

The design illustrated in Figure 4 is particularly adapted for aircraft work as it is not necessary to hold the gear 31 in contact with either meshing gear as the shaft 28 is provided with a recess in which is a spring 35 adapted to be seated in recesses 36 and 37 respectively in the bearing sleeve 30. As shown the shaft is in position for main adjustment and is held against accidental jar-ring away from the enlarged head 11 of the spindle 10 by the spring contacting with the outer wall of recess 36, and when in position for fine adjustment by contacting with the inner wall of the recess 37.

It is understood that the above description and accompanying drawings disclose only the preferred improvement of my invention and that various minor changes in details of construction, proportion, and arrangement of parts may be resorted to within the scope of the appended claims and without sacrificing any of the advantages of my invention.

Having fully described my invention, what I desire to secure by Letters Patent is:—

1. A control mechanism including a support, a shaft journaled in the support, a gear housing affixed to the shaft, a train of gears within the housing for imparting motion thereto, means for rotating the shaft consisting of a spindle journaled in the housing and movable parallel with the shaft, means upon the end of the spindle engageable directly with the end of the shaft for direct rotation thereof by the spindle in its inward position and engageable with the train of gears for the indirect rotation of the shaft

by the spindle in its outward position, the means consisting of a double bevel gear.

2. A control mechanism including a support, a shaft journaled in the support, a gear housing affixed to the shaft, a train of gears within the housing for imparting motion thereto, means for rotating the shaft consisting of a spindle journaled in the housing and movable parallel with the shaft, means upon the end of the spindle engageable directly with the end of the shaft for direct rotation thereof by the spindle in its inward position and engageable with the train of gears for the indirect rotation of the shaft by the spindle in its outward position and means for maintaining the means upon the end of the spindle in pressure engagement with the end of the shaft at the inner position of the spindle.

3. A control mechanism including a support, a shaft journaled in the support, a gear housing affixed to the shaft, a train of gears within the housing for imparting motion thereto, means for rotating the shaft consisting of a spindle journaled in the housing and movable parallel with the shaft, means upon the end of the spindle engageable directly with the end of the shaft for direct rotation thereof by the spindle in its inward position and engageable with the train of gears for the indirect rotation of the shaft by the spindle in its outward position and means for maintaining the means upon the end of the spindle in pressure engagement with the end of the shaft at the inner position of the spindle, and in pressure engagement with one of the train of gears in the outward position of the spindle.

JOHN M. STEWART.
